STRAPLESS BRASSIÈRE SLIP

Harold Roth, New York, N. Y.

Application April 27, 1950, Serial No. 9,525

Term of patent 14 years

(CL. D3—26)

To all whom it may concern:

Be it known that I, Harold Roth, a citizen of the United States, and residing in the city, county, and State of New York, have invented a new, original, and ornamental Design for a Strapless Brassière Slip, of which the following is a specification, reference being had to the accompanying drawings, forming part thereof, and in which:

Fig. 1 is a front elevational view of the strapless brassière slip showing my new design.

Fig. 2 is a rear elevational view thereof.

The leading distinctive feature of the design resides in the provision of vertical elastic panels in the upper body portion of the brassière slip extending from the top to the waistline, at the sides and back of the garment and contrasting in appearance to the intervening panels.

I claim:

The ornamental design for a strapless brassière slip, substantially as shown and described.

HAROLD ROTH.
